(57) **CLAIM**

The ornamental design for an electronic display console and mechanical controller configuration, as shown and described.

DESCRIPTION

FIG. 1 is a front and left perspective view of a first embodiment of an electronic display console and mechanical controller configuration in a vehicle cockpit environment;

FIG. 2 is a rear and right perspective view thereof;

FIG. 3 is a top and front perspective view of the electronic display console and mechanical controller configuration of FIGS. 1 and 2;

FIG. 4 is a front view thereof;

FIG. 5 is a rear view thereof;

FIG. 6 is a right view thereof;

FIG. 7 is a left view thereof;

FIG. 8 is a top view thereof;

FIG. 9 is a bottom view thereof;

FIG. 10 is a top and front perspective view of a second embodiment of an electronic display console and mechanical controller configuration;

FIG. 11 is a front view thereof;

FIG. 12 is a rear view thereof;

FIG. 13 is a left view thereof;

FIG. 14 is a right view thereof;

FIG. 15 is a top view thereof;

FIG. 16 is a bottom view thereof;

FIG. 17 is a top and front perspective view of a third embodiment of an electronic display console and mechanical controller configuration;

FIG. 18 is a front view thereof;

FIG. 19 is a rear view thereof;

FIG. 20 is a right view thereof;

FIG. 21 is a left view thereof;

FIG. 22 is a top view thereof;

(Continued)

FIG. 23 is a bottom view thereof;
FIG. 24 is a top and front perspective view of a fourth embodiment of an electronic display console and mechanical controller configuration;
FIG. 25 is a front view thereof;
FIG. 26 is a rear view thereof;
FIG. 27 is a left view thereof;
FIG. 28 is a right view thereof;
FIG. 29 is a top view thereof;
FIG. 30 is a bottom view thereof;
FIG. 31 is a top and front perspective view of a fifth embodiment of an electronic display console and mechanical controller configuration;
FIG. 32 is a front view thereof;
FIG. 33 is a rear view thereof;
FIG. 34 is a right view thereof;
FIG. 35 is a left view thereof;
FIG. 36 is a top view thereof;
FIG. 37 is a bottom view thereof;
FIG. 38 is a top and front perspective view of a sixth embodiment of an electronic display console and mechanical controller configuration;
FIG. 39 is a front view thereof;
FIG. 40 is a rear view thereof;
FIG. 41 is a left view thereof;
FIG. 42 is a right view thereof;
FIG. 43 is a top view thereof; and,
FIG. 44 is a bottom view thereof.
The broken lines in the drawings are included for the purpose of illustrating portions of the electronic display

console and mechanical controller configuration that form no part of the claimed design.
